UNITED STATES PATENT OFFICE.

LEONARD R. POSCHADEL, OF NEW YORK, N. Y.

TOY.

1,284,444.

Specification of Letters Patent. Patented Nov. 12, 1918.

Application filed March 23, 1918. Serial No. 224,277.

To all whom it may concern:

Be it known that I, LEONARD R. POSCHADEL, a citizen of the United States, and a resident of the city of New York, borough 5 of Manhattan, in the county and State of New York, have invented a new and Improved Toy, of which the following is a full, clear, and exact description.

This invention relates to toys and has for 10 an object the provision of what might be termed a shooting toy as well as a sounding toy whereby a double interest is provided.

Another object in view is the provision of 15 means in the toy whereby a projectile is projected by spring power, but released by the hand either by operating on the projectile direct or through the movable rod.

In the accompanying drawing:

Figure 1 is a side view showing an embodiment of the invention, and illustrating how the same is used.

Fig. 2 is a longitudinal vertical section through the toy embodying the invention.

Fig. 3 is a view similar to Fig. 2, but showing a slightly modified form of toy.

Fig. 4 is a sectional view through the projectile shown in Fig. 3, the section being taken at right angles to the section of Fig. 3.

Referring to the accompanying drawing 0 by numerals, 1 indicates the body of a toy embodying the invention, said body being adapted to be grasped by a hand 2 when the device is in operation, whereby the thumb 3 of hand 2 may press against the body and 5 against the bead 4 of the projectile 5 and release the same from body 1 so that the projectile will be moved or projected by spring 6 along the rod 7, and from thence into the air. The body 1 may be made from any desired material, as for instance wood, and is provided with a bore 8 whereby the upper side walls resiliently grip the projectile 5 which is preferably in the form of a ball, and which is preferably provided with a slot 9 whereby the lower part of the ball is compressed when forced into position as shown in Fig. 2. Ball 5 is made from any material, as for instance rubber, wood, fiber, and the like. It is aimed to provide a structure which will be held in place by friction, which friction may be merely the result of a tight-fitting or the result of the resilient action of the ball. Spring 6 surrounds rod 7 and is preferably provided with a reduced end portion 10 which guides the spring in its movement and acts on the cen-

tral part of the ball so as to project the same longitudinally of the rod. The lower end of the spring may be held in place by any desired means, as for instance by the nut 11 clamped against the bottom 12 of body 1. A nut 13 is mounted on the outer end of the rod 7 opposite nut 11 so as to clamp the same firmly in place, as well as spring 6.

When the parts are assembled as shown 65 in Figs. 1 and 2 it is in condition for operation. To cause the spring 6 to project the projectile 5 from the body a forward movement of the projectile by the thumb would loosen the projectile from the body 1 and 70 the spring will then act to project the projectile a predetermined distance according to the strength of spring 6.

In Fig. 3 a slight modified form of the invention is shown in which the body 1' is 75 provided with a thickened base 14 which acts as a guide for the section 15 of rod 7'. The ball 5' in this form of the invention is preferably not provided with a flange 4 as the ball is released by a movement of the 80 rod when the nut 13 is pressed. Rod 7' is provided with stops 16 and 17 of any desired kind, as for instance annular flanges formed integral with or secured in any desired way to the rod. One of the these 85 flanges overlaps the lower end of the spring 6 while the spring 6 overlaps the upper stop 16.

When the parts are arranged as shown in 90 Fig. 3 and it is desired to cause the projectile 5' to be projected a push on nut 13 will move the rod 7' longitudinally and consequently the stop 16 will press against spring 6 and the spring in turn will press against the ball until it is released from the 95 body 1' after which the spring acting alone will give the proper momentum to the projectile.

What I claim is:

1. A toy comprising a hollow body open 100 at one end and closed at the other, a rod mounted in said body and extending axially thereof, said rod projecting beyond the opening in the body, a spring connected with said body and surrounding said rod, 105 and a projectile loosely fitting on said rod and formed of a size to be normally held in place against the action of said spring by friction in the open end of said body.

2. A toy comprising a body having a bore 110 therein extending from one end, a rod mounted in said body so as to extend longitudi-

nally of said bore and from said body through the open end of said bore, a spring having one end held at the bottom of said bore and the other end freely slideable on said rod, and a projectile having an aperture for 5 accommodating said rod, a slot for causing part of the projectile to be resilient, and a flange for providing operating means whereby the projectile may be loosened by the 10 hand during the operation of the toy.

3. A toy comprising a body having a bore extending from one end toward the opposite end, a rod fitted into said body and extending through the closed end and also through 15 the open end, said rod having a stop at the end adjacent the closed end of the body, and a pair of stops within said bore, a projectile loosely fitted on said rod and engaging the body at the open end of the bore, and 20 a spring arranged in said bore surrounding

said rod, said spring acting on said projectile for projecting the same along said rod and beyond the same, said rod having a limited movement whereby when the same is moved one of said stops will move the projectile until it has become loose, after which the spring will act thereon for projecting it 25 a predetermined distance.

4. A toy of the character described comprising a body having a bore extending from one end toward the opposite end, a projectile mounted in the open end of said bore and held therein by friction, a spring in said bore acting on said projectile and continually having a tendency to move the 30 projectile from the body and project the same through the air, and means extending through the closed end of the body for disengaging the projectile from the body.

LEONARD R. POSCHADEL.
